UNITED STATES PATENT OFFICE.

JOHN M. BEIERMEISTER, OF TROY, NEW YORK, ASSIGNOR TO BEIERMEISTER BROS. & CO., OF COHOES, NEW YORK, A FIRM.

FOLD-COLLAR.

SPECIFICATION forming part of Letters Patent No. 723,575, dated March 24, 1903.

Application filed January 2, 1903. Serial No. 137,493. (No model.)

To all whom it may concern:

Be it known that I, JOHN M. BEIERMEISTER, a citizen of the United States, residing at Troy, county of Rensselaer, and State of New York, have invented certain new and useful Improvements in Fold-Collars, of which the following is a specification.

The invention relates to such improvements; and it consists of the novel construction and combination of parts hereinafter described, and subsequently claimed.

Reference may be had to the accompanying drawings, and the reference characters marked thereon, which form a part of this specification.

Similar characters refer to similar parts in the several figures.

Figure 1 of the drawings is a plan view of a fold-collar opened out flat, so as to expose to view the inner surfaces of its top and band, said collar being made in accordance with my invention. Fig. 2 is a bottom plan view of a similar collar folded and bent to circular form. Fig. 3 is a cross-section of the same, taken on the broken line 3-3 in Fig. 2, the dimensions of the fabric plies being exaggerated for convenience of illustration.

Fold-collars, and more particularly high fold-collars, such as are now in vogue, are made with a band having its upper edge sprung or cambered, so that the top connected with such sprung edge will when the collar is laundered and folded and bent to circular form, as in use, flare downwardly away from the band, which assumes an approximately cylindrical form. In practice, however, it is found that by careless handling in the laundering operation the top edge of the band may be so stretched as to almost entirely eliminate the spring or camber from its upper edge. It is also found that unless the band is heavily charged with starch it will yield to the top in places on account of the greater stiffness of the top, which is usually made of heavier material, causing the band to assume an irregular and sinuous curved form, in some places diverging widely from the top and in others lying in contact therewith. In both instances referred to it is practically impossible to insert a necktie between the top and band of the collar after the col-

lar has been applied to the neckband of the shirt and buttoned thereupon, and so common are the defects referred to that it is the general practice to insert the tie between the top and band of the collar before applying the collar to the shirt or at least before buttoning together the ends of the collar.

The object of my invention is to insure the retention of the spring in the upper edge of the band during laundering and to prevent distortion of the band by reason of the greater stiffness of the top of the collar. This I am able to accomplish by reinforcing the band along its sprung edge, leaving its lower portion of normal thickness—that is, of the thickness ordinarily considered desirable for collar-bands.

Referring to the drawings, 1 represents the top of the collar, made in the usual manner and inserted along its upper edge between the plies of the band 2 and secured thereto by stitching 3 in the usual manner. The upper edge of the band is sprung or cambered, as shown at 4, to a degree sufficient to produce the desired flare of the top when folded and bent to circular form. Along the sprung edge of the band is applied a reinforce 5, comprising one or more plies of fabric, said reinforce being secured along its upper edge to the band by the stitching 3 and along its lower edge by stitching 6. The band thus reinforced is as thick as or thicker than the top and stiffened so that when laundered the sprung edge of the band cannot yield to the top in any part; but the band is enabled to assume and retain an independent position relatively to the top. The reinforcement also prevents the sprung edge of the band from stretching when carelessly handled in the laundering operation, to which result the two lines of stitching 3 and 6 largely contribute, said lines of stitching being located only a short distance apart. The reinforcement is preferably made to terminate at its opposite ends within the confines of the top, as shown, whereby it can be made as thick and heavy as desired without disfiguring the collar or being apparent in use. The reinforcement may be applied directly to the inner side of the band or inserted between the band-plies, as desired. When thus reinforced, the laun-

dered collar will, when folded and bent to circular form, present from end to end a uniform opening along its bottom edge between its top and band, as shown in Fig. 2, which opening 5 renders it comparatively easy to insert the tie after the collar has been buttoned upon the shirt.

In laundering the collar is ironed flat, as shown in Fig. 1, the iron being applied to the outer surface thereof, while the inner surface (shown in Fig. 1) is supported upon a padded bed or a clothed drum, as a result of which 10 operation the inequalities in thickness appear only upon the inner surface. As a result of 15 so ironing the collar the reinforcement above described will form a ridge along the upper edge of the band on its inner side, which ridge even if in contact with the top would insure 20 the separation of the thinner part of the band from the top along the bottom edge of the collar. The reinforcement being applied to the band along its upper edge whereat the band is brought into contact with the neck of the wearer prevents the band from collapsing 25 when moistened by perspiration, as an ordinary band would do.

What I claim as new, and desire to secure by Letters Patent, is—

1. A fold-collar comprising a band of nor-

mal thickness having a reinforced sprung or cambered upper edge, and a foldable top inserted and secured between the band-plies along said reinforced sprung edge, whereby the band is adapted to assume an independent position relatively to the top, substantially 35 as described.

2. A fold-collar comprising a band having a sprung or cambered upper edge; a foldable top; a reinforce applied to the band along its sprung edge; a line of stitching securing together along said sprung edge said band, top and reinforce; and a line of stitching securing together said band and reinforce along the lower edge of the reinforce, substantially 40 as described. 45

3. A fold-collar comprising a band having a sprung or cambered upper edge; a foldable top secured to the band along said sprung edge, and a reinforce applied to the band along its sprung edge terminating at its opposite ends within the confines of said top, substantially 50 as described.

In testimony whereof I have hereunto set my hand this 31st day of December, 1902.

JOHN M. BEIERMEISTER.
